UNITED STATES PATENT OFFICE.

JOHN KIRK, OF TORONTO, ONTARIO, CANADA.

PISTON-VALVE FOR INTERNAL-COMBUSTION ENGINES.

1,186,006.

Specification of Letters Patent.

Patented June 6, 1916.

Application filed February 7, 1914. Serial No. 817,260.

To all whom it may concern:

Be it known that I, JOHN KIRK, a subject of the King of Great Britain, residing at Toronto, in the county of York, Province of Ontario, Dominion of Canada, have invented new and useful Improvements in Piston-Valves for Internal-Combustion Engines, of which the following is a specification.

10 My invention relates to an improved form of gas engine and piston valve therefore and has as its principal object the provision of an arrangement whereby the inlet and exhaust of a gas engine cylinder may be controlled by a single valve.

15 A second object of my invention is to provide a gas engine of maximum simplicity and minimum cost.

20 A final object of my invention resides in the particular arrangement and combination of parts hereinafter described.

In the accompanying drawings:—Figure 1 is a central sectional view of a gas engine cylinder embodying my invention and taken 25 on the line 1—1 of Fig. 2. Fig. 2 is an end view of a gas engine cylinder embodying my invention. Fig. 3 is a cross sectional view of the cylinder shown in Figs. 1 and 2, taken on the line 3—3 of Fig. 2. Fig. 4 is a side view in elevation taken from the right of Fig. 2. Fig. 5 is a central sectional view of my improved piston valve for use in connection with a gas engine. Figs. 6, 7 and 8 are sectional views of the valve shown in 30 Fig. 5, and the valve case thereof, showing the position of the piston valve at various points of the cycle. Figs. 9, 10 and 11 are diagrammatic views showing the position of the operating cam at the same point in 35 the cycle as in Figs. 6, 7 and 8, respectively.

40 Throughout the separate views the same part is designated by a similar reference character.

Referring more particularly to the drawings, 45 1 is a gas engine cylinder which is provided with the ordinary water jacket 2, the inlet of the water jacket being shown at 3. The head of the cylinder carries a valve casting 4 which is shown as integral with the 50 cylinder and which is provided with a cylindrical aperture 5 which may be opened at the ends as shown, and in which is mounted my improved piston valve 6. As shown in Fig. 5, the valve 6 comprises two end portions 7 and 8 which are connected by a cen-

tral bolt or stud 9 on which is slidably mounted a central section 10.

The end portion 8 is recessed at one end as shown at 11 and carries a pin 12 which forms a pivotal connection with a link 13, the link being pivoted in turn to a crank disk 14 carried at one end of the valve operating shaft 15, it being understood that the shaft 15 is driven by suitable gearing from the main shaft of the engine.

60 The head of the engine cylinder and the valve casing are provided with two sets of through ports 16—16 and 17—17, the ports in each set being in alinement as clearly shown in the drawing. Pipes 18 and 19 connect with the ports 16 and 17, respectively, and serve as exhaust and inlet respectively.

65 It will be understood that the shaft 15 makes one revolution while the main shaft of the engine makes two revolutions. 70 Furthermore, it will be seen that the slideable central section of the valve 6 does not occupy the entire space between the end sections 7 and 8, and that the space between the end sections unoccupied by the central section 10 is consequently the same length as the width of the ports 16 and 17. It will be seen moreover, that the end sections 7 and 8 are provided with split spring packing rings 75 80 20—20 while the central section 10 is provided with similar packing rings 21—21. Owing to the friction of the packing rings 21 with the walls of the cylindrical aperture 5, the central section 10 lags behind the movement of the remaining portions of the 85 90 valve so as to give the proper four-stroke operation with a minimum complication and maximum reliability.

95 The cycle of operation is as follows:—As shown in Fig. 3, the piston 22 is shown at the beginning of the suction stroke and the valve 6 is shown at the limit of its stroke in one direction. There is a space 23 between the lower end of the central section 10 and the section 8. As the valve 6 reverses its 100 movement and moves upwardly, it will immediately open the valve 17 so that an explosive charge may be sucked in by the cylinder 22. Figs. 6 and 9 show the position of the valve and the crank disk 14 when the latter has made one-fourth of a revolution from the position shown in Fig. 3. It will be seen now that there is a space 24 between the sections 7 and the central section 10 105 which has been just serving as a port con- 110

necting the ports 17—17, but that in this position the entire valve has moved sufficiently so that the central section 10 has closed port 17, this being the position at the 5 end of the suction stroke. The compression stroke follows immediately after the suction stroke and Figs. 7 and 10 show the relative position of the crank disk 14 and valve 6 at the end of this stroke. It will be ob- 10 served that the crank pin 25 of the disk 14 has moved one-fourth of a revolution and it will be obvious that both the sets of ports 16 and 17 have been closed all during the compression stroke. Figs. 7 and 10 likewise 15 show the valve and crank disk at the opposite expenditure of their movement from that point shown in Fig. 3. Referring now to Figs. 8 and 11 it will be understood that this pair of figures show the valve and crank 20 disk just at the beginning of the exhaust stroke, or at the end of the explosion stroke. The crank pin 25 has moved 90 degrees from the position shown in Fig. 10 and the space 23 is beginning to open and as soon as 25 the crank disk 14 has moved a few degrees farther the opening 23 will begin to register with the ports 16—16 so as to discharge the 30 exhaust gases and by the time the crank pin 25 has moved 90 degrees farther in the direction of the arrow, the valve and piston will have arrived at the same position as shown in Fig. 3, thus completing a four-stroke cycle.

It will be understood that while I have 35 shown and described the preferred form of my invention, that I do not wish to be limited to the mechanical details set forth herein.

Having thus described my invention, what 40 I claim is:—

1. A valve structure comprising in combination, a cylinder having two inlet ports in a given plane transverse to the axis of the cylinder, and two outlet ports in a second

plane transverse to the cylinder, and a piston 45 valve in said cylinder for governing said port, said valve comprising two end portions rigidly spaced apart and an intermediate portion of less length than the distance between said end portions and loosely 50 mounted therebetween.

2. A valve structure comprising in combination a cylinder having two inlet ports in a given plane transverse to the axis of the cylinder, and two outlet ports in a second 55 plane transverse to the cylinder, and a piston valve in said cylinder for governing said ports, said valve comprising two end portions rigidly spaced apart and an intermediate portion of less length than the distance 60 between said end portions and loosely mounted therebetween, said ports and said valve being so arranged that the fluid flows through the gaps between the central portion and the end portions of the valve. 65

3. A valve structure comprising in combination a cylinder having two inlet ports in a given plane transverse to the axis of the cylinder, and two outlet ports in a second plane transverse to the cylinder, a piston 70 valve in said cylinder for governing said ports, said valve comprising two end portions rigidly spaced apart and an intermediate portion of less length than the distance between said end portions and loosely 75 mounted therebetween, said ports and said valve being so arranged that the fluid flows through the gaps between the central portion and the end portions of the valve, a chamber to which said ports connect, and 80 means for operating said valve.

In testimony whereof I affix my signature in the presence of two witnesses.

JOHN KIRK.
